UNITED STATES PATENT OFFICE.

CARL DENZEL, OF FREIBURG, GERMANY.

DENTAL ENGINE.

Application filed May 3, 1924. Serial No. 710,792.

To all whom it may concern:

Be it known that I, CARL DENZEL, a citizen of Germany, residing at Freiburg, Germany, have invented certain new and useful Improvements in Dental Engines, of which the following is a specification.

The present invention has reference to an improvement in the well known electrically driven dental engines, which permit of drilling and the like and also of hot-air blowing, a fan being driven by the motor shaft and the air current generated thereby led over heat resistances on its way to the parts under treatment.

In the prior devices of this character the drill shaft as well as the blower are always operated conjointly, which makes for undue wear and tear and unnecessarily high current consumption, inasmuch as the two operations are hardly ever required simultaneously. My invention provides for the employment of a reversible motor and coupling means for alternately coupling-in the drill shaft or the blower shaft, so that always only the one or the other unit is in operation at the same time.

My invention will best be understood when described in connection with the accompanying drawing, in which Fig. 1 is a more or less diagrammatic vertical section through my improved dental engine; Fig. 2 a cross-section on line A—B of Fig. 1; Fig. 3 is a cross section through coupling *d* of the fan; and Fig. 4 is a cross section through coupling *c*.

The letter *a* denotes the stator member of the motor within which rotates the motor shaft *b*, to the lower extremity of which the flexible shaft (not shown here) is secured by a one-way, for instance right-hand, coupling *c* (Fig. 4). On the upper shaft end is mounted the coupling *d* (Fig. 3) for rotation to the left, with which coacts the hub of the fan *f*.

The motor housing *g* is subdivided by the partition wall *l* and is provided near its upper circumferential edge with air intake ports *i* which are spacedly hooded by the overhanging cover member *h*. To prevent dust and other impurities from being sucked into the housing through these holes *i* there is provided an air-filter *k* back of them. In the upper chamber is mounted the blower unit, and in the lower the motor proper. The partition wall *l* is provided at one side with an aperture *r* communicating with a

funnel-shaped intake *m* to which is connected the air conduit *n* which conveniently ends near the tool end of the flexible drill shaft. A baffle plate *o* extending across the partition wall *l* back of the funnel intake serves to back up the fan driven air to assure its entering the air conduit *m*, *n*. Below the fan there is provided an electric heating unit *p* for warming the fan-trained air prior to its entering, or its issue from, the conduit *m*, *n*. Obviously, the heating unit may also be arranged at some other point in the air passage, and it may be found especially advantageous to dispose it near the discharge or nozzle end of the tube *n*, since in this instance on starting the fan there is an immediate issue of warm air, whereas, if the heating unit is placed higher up in the conduit, the cold air in the lower part of the conduit must first be expelled.

To operate the device a reversing switch of any suitable make is used, the wire connections of which are such that upon starting the motor in the direction, right or left as the case may be, for operating the blower, the heating unit is simultaneously cut-in whilst both units, the blower and the heater, are cut-out upon the motor being reversed for operating the flexible tool shaft.

What I claim is:

1. In a dental engine of the character set forth, in combination with a reversible motor and switch means for controlling the operation and direction of rotation of said motor, a tool shaft, a blower, and independent coupling means interposed between said motor and said tool shaft and between said motor and said blower respectively, for selectively coupling said motor to said tool shaft or to said fan according as said motor runs in the one or the other direction.

2. In a dental engine of the character set forth, in combination with a reversible motor and switch means therefor, a tool-operating coupling actuated by said motor on operation thereof in one direction, a blower unit, comprising a fan, an air conduit and a heating member, and a fan-operating coupling actuated by said motor on operation thereof in the respective other direction.

3. In a dental engine of the character set forth, in combination with a reversible motor and switch mechanism therefor, a flexible drill shaft, a blower unit, and coupling means respectively interposed between said

motor and said flexible shaft and between said motor and said blower unit for selectively independently operating said flexible shaft and said blower unit according as said motor rotates in the one or the other direction, said blower unit comprising a fan, an air conduit, and a heat member for heating the fan-impelled air prior to its reaching the issue end of said conduit, and said heat member operable only during the operation of said fan.

4. In a dental engine of the character set forth, in combination, a housing presenting screened air-intake ports, a partition wall dividing said housing into two superposed chambers, a reversible motor including a shaft in the lower chamber, a blower in the

upper chamber, the upper end of said motor shaft extending into said upper chamber, and the lower end of said motor shaft extending outside of said housing, a one-way coupling member on this external shaft end, a one-way coupling member on the upper end of said motor shaft for coaction with said blower, said two coupling members designed for respectively alternate operation only; said partition wall presenting an air port, an air conduit communicating with this air port, and a baffle plate flanking the air port, and a heating unit interposed between said blower and the issue end of said air conduit and operable only during operation of said blower.

CARL DENZEL.
